UNITED STATES PATENT OFFICE.

GEORG KIRKEGAARD, OF NEW YORK, N. Y., ASSIGNOR TO IMPERIAL STOPPER COMPANY, A CORPORATION OF MAINE.

CAPPING-MACHINE.

No. 922,778.

Specification of Letters Patent. Patented May 25, 1909.

Application filed May 6, 1908. Serial No. 431,149.

To all whom it may concern:

Be it known that I, GEORG KIRKEGAARD, a citizen of the United States, residing at the city of New York, in the borough of Brooklyn and State of New York, have invented 5 certain new and useful Improvements in Capping-Machines, of which the following is a full, clear, and exact description.

This invention relates to bottle capping machines of that class which are adapted to apply a cap or stopper to a bottle, particularly caps having a circumferential depending flange adapted to make locking engagement with the exterior of the neck of the 15 bottle, and containing a packing disk which is held under compression against the mouth of the bottle by such locking engagement. In machines of this character, especially those which are driven by power, the stroke 20 of the plunger and head which applies the cap to the bottle is usually of uniform length, and, if the bottle happens to be of abnormal length, as often occurs, unusual pressure is exerted thereupon by the machine, which results in breakage and loss. 25

It is the object of my invention to provide a machine which, while affording the necessary pressure to compress the packing disk and apply the cap, will automatically compensate 30 for the variations in the length of the bottle and prevent the breakage and loss referred to.

The invention consists in supporting a bottle upon a table which is freely depressible through a range or distance of movement 35 great enough to accommodate the greatest variations in the length of the bottles which are capped. In conjunction with this depressible table, I provide a means for automatically locking the same in a fixed position at a predetermined point or stage in the bottle-capping operation, this locking action occurring automatically after the parts have assumed a proper relation to one another by 40 the preliminary manipulations necessary in positioning the bottle. In practice I make the table yieldingly spring pressed upward and provide a locking device which is put into operation at the instant that the cap is 45 about to be bent or engaged upon the bottle. This arrangement, not only compensates with certainty for all variations and irregularities in the bottles and in the caps, but also facilitates the preliminary manipulation 50 of positioning the bottle, and renders it pos-

sible to use a capping machine with a comparatively short, slow, powerful stroke, instead of a stroke of greater length and velocity with proportionate vibration and impact on the fragile glass. 60

In the drawings; Figure 1 is a vertical sectional view of the essential parts of a bottle capping machine embodying the principles of my invention. Fig. 2 is a detail view showing a modified form of locking 65 means.

Referring to the drawings, in which like parts are designated by the same reference sign, 1 indicates a cap-applying head having a forming or compressing die 2 of any desired or preferred construction. The cap-applying head is adapted to be reciprocated through any suitable power or other means not forming part of the present invention. A practical means for this purpose is set 70 forth in my companion application Serial No. 431,147. 75

3 designates the depressible table which is yieldable in the direction of movement of the cap-applying head 1. In practice I 80 make the table 3 with a hollow stem or plunger 4 slidably received in a socket 5 forming a fixed part of the machine.

6 denotes a spring within the hollow plunger 4, by which the latter is normally 85 maintained in an elevated position, but yieldable downward when a slight amount of force is applied thereto.

7 designates a screw entering a recess 7' in the plunger 4, so as to limit the vertical 90 movement thereof.

In conjunction with the depressible plunger 4 I provide a locking device adapted to engage the plunger and fix its position at a predetermined point or stage in the capping 95 operation. My preferred construction for this purpose comprises a solenoid magnet 3 fixed to the frame or socket 5 by a bracket 9.

10 denotes a core or armature of magnetic material guided by the bracket 9 and movable axially through the solenoid. At its inner end this armature has a dog or toothed portion 11 adapted to engage a correspondingly toothed section 12 of the plunger 4 constituting a rack for the table. The dog 105 11 is, however, normally kept in its retracted position out of engagement with the teeth 12, by a spring 13 acting against a head or enlargement 14 at the outer end of the armature 10. Whenever the solenoid is 110

energized, the armature 10 is attracted to the left in Fig. 1, and the dog 11 engages the teeth 12 to lock the plunger against any movement of depression.

5 The solenoid 8 may be included in a circuit which is closed by devices within the cap-applying head. I have illustrated a convenient practical construction, making use of a permanent magnet 16 which is slideable endwise in a shaft 17 forming part of the cap-applying head. This permanent magnet normally falls by gravity to its lowermost limit of movement, determined by a stop 18. In this relation the poles of 10 this magnet are conveniently presented to receive a bottle cap 19 and support the same preliminary to its application on the bottle. The magnet 16 has a contact 20 supported thereby in any suitable way, and directly 15 above this contact I provide a stationary contact 21 which, however, may be made adjustable on a supporting insulating block 23. 20 24 designates a spring which permits a slight upwardly yielding movement of the block 23.

25 The contacts 20 and 21 are made the terminals of an electrical circuit including the solenoid 8 and a battery 25. When these contacts are brought together the circuit is completed and the solenoid is energized.

30 The use and operation is as follows: Assuming that the parts are in their normal relation, a cap is first placed beneath the magnet 16 and attracted and held thereby, after which a bottle 26 is forcibly depressed upon the table 3 which yields under the application of the pressure so applied. If this force upon the bottle is now released, the 35 latter rises under the influence of the spring 6, until its neck or mouth enters the cap 19 which is suspended from the magnet 16, as above noted. It is obvious that the parts will assume this relation regardless of any 40 variations in the length of the bottle 26 or in the thickness of the caps. If the machine is now started in operation, the cap-applying head 1 will descend. In this action the magnet 16 will first rise to its upward limit 45 of movement and bring the contacts 20 and 21 into engagement, completing the electrical circuit of the solenoid 8. At the instant, therefore, that the forming die 2 becomes effective and commences its compressing and 50 cap-applying action, the locking dog 11 is thrust forward into the path of the teeth 12, so that the table 2 is prevented from yielding downward. The cap-applying head thereafter descends through a fixed throw 55 requisite to complete the application of the bottle cap, the amount of this throw being, however, of limited and exactly predetermined range or extent, depending on the character of the cap to be applied.

60 65 By the above described mechanism all ir-

regularities in the bottles are compensated for by the preliminary part of the action of the machine, the final step of applying the cap being made by an unvarying action or performance of the machine, as is desirable. 70 It will be noted that the nature of this final cap-applying action or performance of the machine is such as to require only a very limited movement of the cap-applying head, so that the latter has very little inertia or 75 impact against the fragile glass of the bottle, which might break or damage the same.

In Fig. 2 I have illustrated a slightly modified construction of locking means for the compressible plunger 4. In this case there 80 may be provided a pivoted locking dog 11' to engage the toothed section 12 of the plunger 4. The armature 10' is pivoted to the dog 11' so as to tilt the latter into engagement with the teeth 12 when attracted into 85 the solenoid. The movement of the core or armature 10' in this instance is toward the right, instead of toward the left as in Fig. 1, the spring 13' being correspondingly located on the left of the solenoid to impart a proper 90 return movement to the core or armature.

What I claim is:

1. In a bottle capping machine, a cap applying head, a table yieldable in the direction of movement of said head, locking means for securing said table against a movement of depression, a magnet for actuating said locking means, and means actuated by the descent of said cap-applying head upon a bottle for completing a circuit 95 through said magnet.

2. In a bottle capping machine, a cap applying head, a table resiliently yieldable in the direction of movement of said head, locking means for securing said table against 100 a movement of depression, a solenoid for actuating said locking means, and means actuated by the descent of said cap-applying head upon a bottle for completing a circuit through said solenoid.

3. In a bottle capping machine, a cap applying head, a table yieldable in the direction of movement of said head, means in said head for completing a circuit at the instant when said head commences its cap-applying 115 function on a bottle, and means for locking said table against yielding movement when said circuit is completed.

4. In a bottle capping machine, a cap applying head, a table compressible in the direction of movement of said head, a solenoid having an armature with a dog, a rack adapted to be engaged by said dog to prevent a movement of depression of said table, and means for completing a circuit through 120 said solenoid when said head commences its cap-applying function on a bottle.

5. In a bottle capping machine, a cap applying head having a forming die, a magnet 125 slideable inwardly from said forming die,

a circuit completed by such inward movement of said magnet, a depressible table, and means actuated by the completion of said circuit for locking said table against a movement of depression.

6. In a bottle capping machine, a cap applying head having a forming die, means depressible inwardly within said die and having a contact, another contact in the path 10 of said first named contact, a depressible

table, and a circuit completed by said contacts and adapted to lock said table against a movement of depression.

In witness whereof, I subscribe my signature, in the presence of two witnesses.

GEORG KIRKEGAARD.
